UNITED STATES PATENT OFFICE.

KIMBALL OYLER, OF LOS ANGELES, CALIFORNIA, ASSIGNOR TO THE GOODYEAR TIRE & RUBBER COMPANY, OF AKRON, OHIO, A CORPORATION OF OHIO.

CALENDER KNIFE.

Application filed June 8, 1925. Serial No. 35,621.

My invention relates to attachments for mills and calenders such as are commonly employed in the rubber industry and it is particularly directed to means for cutting 5 and removing the plastic material.

The object of my invention is to provide an improved trimmer to sever selvage, or bands of rubber, from a portion being calendered or worked on a mill.

10 Before a rubber composition is vulcanized, it is necessary to incorporate the vulcanizing ingredients, accelerators, and fillers. In addition, it is common practice to give the raw material its final shape before destroying 15 its plastic properties. By far the larger number of these operations are carried out on mills or calenders. Not only are mills employed in incorporating the various compounding ingredients, but foreign matter 20 is often washed out of the plastic in a manner not unlike that utilized in compounding processes.

In all such cases, a certain amount of the milled product is extruded near the ends of 25 the rolls and must be removed. Moreover, where a calendered sheet is being prepared, the product must have a smooth edge. In the past this trimming has been effected in more or less improvised manner. According 30 to the present invention, I have mounted a knife or suitable severing device in resilient relation with the calender rolls and thereby have been able to secure uniform results.

In the attached drawings:

35 Fig. 1 is a side view showing the particular relation of my device with the mill rolls; and

Fig. 2 is a perspective view, on somewhat 40 a larger scale, of a device constructed according to the principles of my invention.

The device comprises an elongate supporting member 1, having a pair of parallel lug plates 2 rigidly joined therewith. Each of the lugs is provided with an opening 45 within which a stem 3 of an ovate knife is supported. That portion of the stem of the knife contained within the parallel lugs, is surrounded by a helical spring 4. A cotter key 5 engages the stem of the knife 50 through holes provided therefor and is adapted to retain the knife in adjusted operable position. It will be noted that the key tends to limit the forward motion of the knife against the force of the spring.

The device may be held in position in any 55 suitable manner. For example, the supporting member 1 is provided at one end with an inverted U-formation 6 which is adapted to engage a pan 7, in a manner illustrated in Fig. 1. It may be secured in this position 60 by a set screw 8 disposed in an opening 9 having suitably threaded walls.

In practicing my invention, it will be noted that as the roll moves in the direction 65 of the arrow, the overflow is severed by the ovate knife, the severed material being, at the same time, removed by a cooperating scraper 10, which is bolted to a suitable support 11. The trimmer may be adjusted in 70 any position along the pan and in case it is to be employed in making bands or strips no scraper will be found necessary. In the latter event, the several trimmers are adjusted in spaced relation, depending upon 75 the width of the band desired.

It will be noted that by practicing my invention there is at all times a constant pressure between the knife edge and the roll. Moreover, the pressure may be adjusted in order to prove effective against any thickness 80 of rubber.

It is obvious that although I have disclosed but a single embodiment of my invention, it may be subjected to wide variations without departing from the principles herein set forth, and I desire, therefore, 85 that it shall be limited only in accordance with the appended claims.

What I claim is:

1. A trimming device for calendering machines comprising an elongate knife member adapted for linear movement, resilient means for maintaining the latter in engagement with the roll of the calender, and a scraper operative in conjunction with the 90 knife for removing scraps from the roll.

2. A device for cutting rubber comprising an elongate supporting member having projecting integral lugs and an end of inverted U-shape, a knife having a stem provided with a series of spaced openings mounted in openings provided in the lugs, a spring mounted about the stem of the knife between the lugs and a pin disposed in one of the 95 openings in the stem and in engagement with the spring.

3. The combination with a trimming device adapted to engage a calender roll, of a

scraper operatively associated with the trimming device and adapted to engage the roll to remove scraps of severed material from the latter.

5 4. A trimming device adapted to be attached to a calendering machine having a pan thereon, said device comprising an arm

having a knife at one end, and means including a U-shape clamp member secured transversely to the arm for clamping the 10 arm to the edge of the pan.

In witness whereof, I have hereunto signed my name.

KIMBALL OYLER.
